UNITED STATES PATENT OFFICE.

BURNIE J. CRAIG, OF CLEVELAND, OHIO.

RUNNING SHOE.

Application filed April 18, 1922. Serial No. 555,080.

To all whom it may concern:

Be it known that I, BURNIE J. CRAIG, a citizen of the United States, residing at Cleveland, in the county of Cuyahoga and

5 State of Ohio, have invented a certain new and useful Improvement in Running Shoes, of which the following is a full, clear, and exact description, reference being had to the accompanying drawings.

10 This invention relates to shoes and particularly to athletic shoes such as are worn by contestants in sporting events wherein the speed attained in running is an important factor of the sport.

15 The general object of the invention is to provide a shoe for athletes which will enable the wearer to secure the maximum results from the energy expended.

In running it is essential that the stride, 20 or step, of a runner be as long as possible and this invention contemplates the provision of means on a running shoe which will enable the stride of a runner to be lengthened materially without unduly increasing the effort required to produce the increase in stride.

In running shoes heretofore constructed, the spikes have been merely large tacks which were circular in cross section and 30 which tapered from their point of attachment to the shoe to the end which was somewhat sharpened. In running at top speed, a runner's foot strikes the ground with the sole of the shoe almost parallel with the track. When the shoe strikes in this manner, the spikes are not pushed in vertically but are advanced to position by cutting through the track. In completing the stride and before the cutting action is entirely completed, the shoe turns with the 40 toe as a pivot until, when the runner springs for his step only the end portion rests upon the ground. The sole of the shoe meanwhile becomes somewhat arched from the flat position it took when the slide mentioned was started.

With the former shoe, the resistance offered the cutting action mentioned caused by the round spikes, interfered somewhat 45 with the runner and when he moved onto his toe to secure the push for the next step, the shoe slipped back a slight distance; no material resistance being offered by the rounded surface of the spikes. The round surface merely acts to stir up the ground

and does not provide a good surface from which to spring.

The object of the invention is to overcome the difficulties mentioned by constructing a spike which is preferably stream line in front so that when it strikes and cuts through the ground, the surface is merely parted as by a knife so that the act of placing the foot on the ground does not distract the runner's balance. The rear of the spike 60 is made plane or concave of such section that it will pack the ground when it is pushed rearwardly. Each spike is preferably arranged with its rear perpendicularly to the sole, while the front of the spike 65 makes an acute angle with the rear surface and this enables the spike to have a thick root and a sharp point. With this improvement, the spike pierces the track easily and the runner in springing forward 70 has a packed surface to push from which serves to react against the forward push. This enables him to utilize the full amount 75 of the energy derived from his muscles.

Further and other objects of the invention will be apparent from the following specification taken in connection with the accompanying drawings wherein Fig. 1 is a bottom plan view of a running shoe embodying the features of my invention; 80 Fig. 2 is a side elevation of the shoe; Fig. 3 is an enlarged section; Fig. 4 is a side elevation of a spike; Fig. 5 is a rear elevation and Fig. 6 is a perspective view of the same 85 spike; Fig. 7 is a perspective view of a modified form of spike, and Fig. 8 is a view showing the effect produced when one of the spikes is inserted in the ground in the act of running.

Referring to the drawings by reference characters, I have shown a running shoe 90 5; which may comprise an upper 10 provided with an inner sole 11 and an outer sole or tap 12.

The spikes, shown at 15, are preferably made of metal and may be provided with a head 16 or other means for anchoring them in place. The spikes are shown with the head secured between the inner sole and the tap sole with the point piercing the latter. The rear surface 30 of the spikes is preferably constructed to be perpendicular to the sole of the shoe when secured in place and this rear surface may be plane, as shown at 110

21 in Fig. 7, or as I now prefer it may be concave, as at 22; Fig. 6.

The front of the spike is shown as making an acute angle 23 with the back. For the best results, I now prefer to make the spike concave-convex in cross section at the point and gradually merging into a substantially concavo-triangular sectional shape at the root. When arranged in the shoe, the concave surface faces the rear.

It is desirable to provide means to prevent the spikes turning from their proper position. To do this, apertures 25 are made in the head and through the apertures nails 26 are inserted.

Any number of spikes may be used in a shoe, arranged in any desired manner. In the drawing, I have shown six spikes in two diverging columns. In constructing a shoe, the tap sole may be provided with apertures through which the spikes may be inserted. The nails 26 may then be placed in position, the spike being thus secured against turning. After this operation, the tap sole may be secured to the shoe. Other means for securing the spikes in place will be apparent to the shoemaker but at present I prefer to construct the shoe as set forth.

As stated above, in running the runner drags his foot above the ground just before the spike is inserted. This is shown on a somewhat exaggerated scale in Fig. 8, wherein at 30 a spike is shown just entering the ground as the runner puts down his foot. At 31, the spike is partly inserted and at 32 the spike is fully in the ground. The shaded portion 33 indicates the area in the rear of the spike which has been loosened.

With my improved construction, the extent of this area is much reduced and in pushing rearwardly in taking his next stride the runner packs the ground with the rear surface of the spike and consequently his grip is better and a longer stride results. The advantage gained with each step in using the improved shoe is of course quite small, but as the running races are seldom less than 100 yards, the distance gained with each step is multiplied many times and amounts to a matter of several feet during a race. This added distance is of great importance to the runner.

Having thus described my invention, I claim:

55 1. A running shoe comprising a flexible

light upper having a light sole secured thereon; a rigid gripping spike on said sole and projecting therefrom, said spike having a flat head, means for securing the head of the spike to the sole, the shank of said spike being non-circular in cross section and having distinctly defined front and back portions, the front of the spike being more or less sharp to part the surface of the ground as the shoe strikes it and the back of the spike having no portion projecting rearwardly beyond the side edges of the spike.

2. A running shoe comprising a flexible light upper having a light sole secured thereon; a plurality of individual, spaced, metallic gripping spikes on said sole and projecting therethrough, said spikes having flat heads secured to the light sole, each of said spikes being substantially concavo convex in cross section with the convex portion disposed in front and the concave part being disposed in the rear so that the spikes pack the ground when the shoe is pushed rearwardly.

3. A running shoe comprising a flexible light upper having a light sole secured thereon, a plurality of gripping spikes on said sole and projecting therefrom, means for securing the spikes to the sole, said spikes tapering uniformly from their root to the point, the front of each spike being more or less sharp to part the surface of the ground as the shoe strikes it and the rear of each spike being arranged substantially perpendicular to the sole of the shoe to resist dragging through the ground when the spikes are pushed rearwardly, and means on said spikes to prevent them turning relative to the sole.

4. A running shoe comprising a flexible light upper having a light sole secured thereon, a plurality of gripping spikes extending through said sole and projecting therefrom, a flat head on said gripping spikes for securing them to the sole, said spikes tapering from their point to their root, said point being sharpened, the spikes near their point being concavo-convex in cross section and the spikes near their roots having a concave rear side and an angular front side.

In testimony whereof, I hereunto affix my signature.

BURNIE J. CRAIG.
